UNITED STATES PATENT OFFICE

JOHN A. MINSHULL, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS

ECCENTRIC CONNECTION FOR CARD CONDENSERS

Application filed July 3, 1929. Serial No. 375,690.

This invention relates to an eccentric connector capable of general application but particularly designed for use in a card condenser. In such machines, the apron rolls are oscillated or reciprocated axially at high speed, the number of reciprocations being commonly above 300 per minute.

Eccentric connections have been used to produce such reciprocations, but trouble has 10 been encountered from overheating if the rate of reciprocation was increased substantially above 300 reciprocations per minute. This was a serious limitation, as an increase in the speed of reciprocation of the apron 15 rolls was frequently very desirable.

A general object of my invention is to provide a form of eccentric connector operable at a higher speed than the old form of connector and without overheating.

20 A further object is to provide for more effective and reliable lubrication of such an eccentric connector.

My invention further relates to arrangements and combinations of parts which will 25 be hereinafter described and more particularly pointed out in the appended claims.

A preferred form of the invention is shown in the drawings in which—

Fig. 1 is a plan view of my improved eccentric connector, together with portions of a 30 card condenser;

Fig. 2 is a side elevation, partly in section, of the construction shown in Fig. 1; and

Fig. 3 is an end view of one of the eccentric 35 members, looking in the direction of the arrow 3 in Fig. 1.

Referring to the drawings, I have indicated a portion of a pair of aprons 10 and 12, mounted upon suitable rolls 13 secured at one 40 end in a cross head 15, by which said rolls and aprons may be reciprocated. A drive shaft 20 is mounted to rotate about an axis perpendicular to the plane of movement of the aprons and is provided with an adjustable 45 double eccentric for each apron.

The two parts of each eccentric may be relatively adjusted to vary the throw of the eccentric and thus determine the amount of reciprocating movement of each apron, but the 50 tails of construction of the adjustable eccen-

trics form no part of my present invention and need not be further described.

My improved eccentric connector comprises eccentric members 30 and 32 which are secured together in definite spaced relation by 55 binding bolts 34 and a plurality of nuts 36, some of which act as lock nuts.

The eccentric member 30 is adjustably secured to the shank 40 of a member 41, pivoted to the cross head 15 by a stud 42. The parts 60 30 and 40 may be adjustably secured to each other by set screws 44 or in any other convenient manner.

It will be noted that each of the eccentric members 30 and 32 engage the eccentric over 65 somewhat less than one third of its circumference and that consequently somewhat more than one third of the surface of the eccentric member is free at all times when the machine is in operation. This in itself tends to a cooler 70 running of the eccentric, as somewhat more than one third of its circumference is at all times exposed to the atmosphere.

I have also provided novel and very effective oiling means for my improved eccentric 75 connector. For this purpose I provide an oil well or recess 50 in the upper side of each eccentric member 30 or 32, this oil chamber extending down substantially to the center of the thickness of the connector and having an 80 oil hole 52 leading from each end of the oil well to a portion of wick or other similar material 54, secured to the ends of the eccentric members 30 and 32 by clamps 56 and screws 57, or in any other convenient manner. 85

As these eccentrics commonly oscillate in a horizontal plane and are driven by a vertical shaft, the oil chambers 50 in the upper faces thereof are well adapted to receive and distribute the necessary lubricant. The oil is 90 conveyed through the oil passages 52 to the wicks 54 by which a thin film of oil is transferred direct to the surface of the eccentric.

While an oil connection and wick at the 95 leading side of each eccentric member might be sufficient where an eccentric is always rotated in a single direction, I find it desirable to use an oil passage and wick at each side of the connector, thus making the device reversible and also providing for wiping the 100

eccentric as it leaves the eccentric member, as well as for providing oil to the eccentric as it enters the bearing portion of the eccentric member.

5 The second wick tends to retain the oil in the bearing segment between each eccentric member and the rotating eccentric and to keep the eccentric wiped clean of oil and dust when open to the atmosphere.

10 It has been found that an eccentric connection of the type above described is capable of use at a substantially higher speed than the old type of connector. Under actual test my improved connector runs without overheating at 450 R. P. M. and would apparently run at a substantially greater speed, while the old type of connector began to seriously overheat if run above 325 R. P. M.

Having thus described my invention and 20 the advantages thereof, I do not wish to be limited to the details herein disclosed, otherwise than as set forth in the claims, but what 15 I claim is:—

1. In a connector for a driving eccentric 25 operable in a horizontal plane and comprising a pair of connecting members and means to secure said members in spaced relation, lubricating means for said members and eccentric comprising an open oil well in the 30 upper side of each connecting member, and means to distribute oil from said wells to the bearing surfaces of said member and said eccentric.

2. A connector for a driving eccentric 35 operable in a horizontal plane and comprising a pair of connecting members, means to secure said members in spaced relation, and means to lubricate said members and eccentric, said lubricating means comprising an oil well in 40 the upper side of each connecting member, and a piece of wick material secured to each end of each connecting member, said member having oil passages connecting said oil well to each piece of wick material.

45 3. A connector for a driving eccentric operable in a horizontal plane and comprising a pair of connecting members, means to secure said members in spaced relation, and means to lubricate said members and eccentric, said lubricating means comprising a wiping element secured to each end of each connecting member, and means to supply oil through 50 said wiping elements to said eccentric, certain of said wiping elements being also operable to remove excess oil from the bearing surface of said eccentric as it leaves bearing engagement with each of said connecting members.

In testimony whereof I have hereunto affixed my signature.

JOHN A. MINSHULL.
